UNITED STATES PATENT OFFICE.

WILHELM DIETZ, OF LEUTZSCH, NEAR LEIPZIG, GERMANY, ASSIGNOR TO KÖRTING & MATHIESEN AKTIENGESELLSCHAFT, OF LEUTZSCH, NEAR LEIPZIG, GERMANY.

ARC-LAMP.

1,191,289.

Specification of Letters Patent. Patented July 18, 1916.

Application filed April 30, 1914. Serial No. 835,469.

To all whom it may concern:

Be it known that I, WILHELM DIETZ, a subject of the German Emperor, residing at 9 Bismarckstrasse, Leutzsch, near Leipzig, 5 Germany, have invented a new and useful Arc-Lamp, of which the following is a specification.

This invention has for its object to affect the light (by which is meant either extinguishing the lamp or decreasing or increasing the light given by it) given by one or more arc lamps connected in series without affecting that of the others. According to this invention this is effected by momentarily changing the strength of the current. For this purpose there may be employed a pair of magnets and a movable member adapted to be moved to and fro under the influence of the magnets, the momentary 15 abnormal current causing the movable member to directly or indirectly close a circuit which permanently affects the strength of one of the magnets. One magnet is preferably the main lamp magnet, the other the shunt magnet and the movable member the carbon feed regulator.

The invention is particularly applicable for street lighting in which it is desired either to extinguish at a given hour some or 20 all of the lamps in the series or to make some or all of the lamps burn with diminished brilliancy.

The invention is illustrated in the accompanying drawings in which—

35 Figure 1 shows a lamp circuit to one or more of whose lamps the invention may be applied; Fig. 2 shows a lamp which can be extinguished by a momentary rush of current and Figs. 3 and 4 show lamps which 40 can be made to give less light by the same means.

In Fig. 1, 1 is the primary winding of a transformer for constant current, 2 its movable secondary and *a b c d e* are lamps in 45 series connected to the secondary winding 2. The lamps *a c e* for example may be lamps in accordance with this invention so that these can be extinguished while the lamps *b* and *d* continue to burn. Or all or some of 50 these lamps may be made to burn with half their usual brilliancy.

In the drawings lamps are shown in which the abnormal current is a sudden rush of current and the lamp is either extinguished or made to give a decreased light. 55

In Fig. 2, 3 is a disk, 4 is the main lamp magnet, 5 a shunt magnet; the disk 3 is adapted to move about its axle 6 anticlockwise under the influence of magnet 4 and clockwise under the influence of magnet 5. 60 7 is a quadrant moving with the disk 3 and operating a chain 8 and thus the clutch 9 of the upper carbon 10 which through a chain 11 passing over a pulley 12 is connected to the lower carbon. 13 is a contact 65 moved by the disk 3 and 14 is a small resistance. 15 and 16 are the main lamp terminals. 17 and 18 are contacts in the path of the movable contact 13.

The disk 3 oscillates under the influence of 70 the magnets 4 and 5 to regulate in the usual manner the carbon feed. When however a rush of current is purposely transmitted from the central station the magnet 4 moves the contact 13 to an abnormal extent thus causing it to make contact with the contact 18. The lamp is now extinguished being short circuited upon the resistance 14 thus depriving the shunt magnet 5 of nearly all current which has for effect that the magnet 4 80 when again energized to the normal extent will continue to hold the contact 13 firmly against the contact 18. If a carbon burns out the lamp voltage becomes higher than the normal thus causing the magnet 5 to become 85 stronger and the disk 3 to move clockwise bringing the contact 13 against the contact 17 thus extinguishing the lamp. The magnet 4 will now receive no current while by arranging that the resistance 14 shall cause a 90 fall in tension about 4 to 6 volts, the magnet 5 is given the necessary strength to hold the contacts 13 and 17 together.

In the lamp illustrated in Fig. 3, the parts marked 3 to 17 are equivalent to those so 95 marked in Fig. 2. The magnet 5 is as before normally excited by a winding indicated in this figure by 24 and can also be excited by a second winding 25 terminating in a contact 22. 26 is a contact arm adapted 100 to move about a pivot and provided with a tail 27 in the path of abutments 28 and 29

moved by the chain 8. Exactly in the same manner as in Fig. 1 a rush of current will cause the disk 3 to move anticlockwise thus lifting the chain 8 and causing the abutment 5 28 to strike the tail 27 thus operating the contact arm 26 and moving it against the contact 22 switching in the auxiliary winding 25. The magnet 5 is now energized by its two windings causing the disk 3 to rotate clockwise. With the normal lamp current the length of the arc will now be permanently reduced and therefore the lamp will give less light than before. When the lamp is switched out the carbon clutch 9 10 falls and the abutment 29 strikes the tail 27 of the contact arm 26 thus moving it away from the contact 22. When the carbons are consumed the contact 13 will come against the contact 17 and thus switch out 15 the lamp.

Fig. 4 is a modification of the lamp shown in Fig. 3 in which mechanically operated contacts are avoided. Similar figures indicate similar parts. 19 is a lever arm pivoted 25 at 20 and carrying the core 21 of a solenoid 23. When a rush of current is sent the disk 3 rotates anticlockwise and the contact arm 13 raises the lever arm 19 about its pivot so making contact between the arm carrying 30 the core 21 and the contact 22. Current can now pass through the winding 25 and the solenoid 23 in series with it. This has for effect to rotate the disk clockwise and to hold the core 21 in position thus permanently shortening the arc and diminishing 35 the light.

When in the claims I speak of altering the light given by the lamp, I mean either extinguishing the lamp or decreasing or increasing the light given by it.

What I claim is:—

1. In an arc lamp system, a plurality of lamps in series, certain of said lamps being provided with means operated by the electrode feeding mechanism for altering the amount of light given by the lamp on a change of current from normal, means for supplying a current of normal strength to the series of lamps and including means for 45 momentarily varying the current from normal to operate said light altering means.

2. In an arc lamp system, a lamp having electrode feeding means, said means including a main lamp magnet, means operated by 55 the electrode feeding mechanism for altering the amount of light given by the lamp on a change of current from normal through said magnet, means for supplying a current of normal strength to the series of lamps and 60 including means for momentarily varying the current from normal to operate said light altering means.

3. In an arc lamp system, a plurality of lamps in series, electrode feeding means for

said lamps, said means including a pair of 65 magnets and a movable member operated thereby, certain of said lamps being provided with means operated by the electrode feeding mechanism for altering the amount of light given by the lamp on a change of 70 current from normal, means for supplying a normal current to the series of lamps and including means for momentarily varying the current from normal to operate said light altering means. 75

4. In an arc lamp system, a plurality of lamps in series, electrode feeding means for said lamps, said means including a pair of magnets and a movable member operated thereby, certain of said lamps being provided with means operated by the electrode feeding mechanism for altering the amount of light given by the lamp on a change of 80 current from normal, said means comprising a switch member operated by said movable member, means for supplying a normal current to the series of lamps and including means for momentarily varying the current from normal to operate said light altering 85 means. 90

5. In an arc lamp system, a plurality of lamps in series, electrode feeding means for said lamps including a pair of magnets, certain of said lamps being provided with means operated by the electrode feeding means for 95 changing the strength of current through one of said magnets for altering the amount of light given by the lamp on a change of current from normal, means for supplying a current of normal strength to the series of 100 lamps and including means for momentarily varying the current from normal to operate said light altering means.

6. In an arc lamp system, a plurality of lamps, certain of said lamps being provided 105 with means operated by the electrode feeding mechanism for altering the amount of light given by the lamp on a change of current from normal, said means comprising a switch, means for supplying a current of 110 normal strength to the series of lamps and including means for momentarily varying the current from normal to operate said light altering means.

7. In an arc lamp system, a plurality of 115 lamps, certain of said lamps being provided with means operated by the electrode feeding mechanism for altering the amount of light given by the lamp on a change of current from normal, said means comprising a 120 short circuiting device, means for supplying a current of normal strength to the series of lamps and including means for momentarily varying the current from normal to operate said light altering means. 125

8. In an arc lamp, electrode feeding mechanism comprising a series and shunt magnet, and a pivoted member movable in one

direction by the series magnet to separate the electrodes, and movable in the other direction by the shunt magnet to feed the electrodes, a movable switch member operated by said pivoted member, a switch contact in position to be engaged by the movable switch member on movement of the feeding mechanism in a direction to separate the elec-

trodes, upon the passage of current above that which separates the electrodes a normal 10 arcing distance.
